UNITED STATES PATENT OFFICE

JOHN COTTER FELTON, OF SANTA BARBARA, CALIFORNIA, ASSIGNOR TO PEREZ ROGERS
BABCOCK, OF SANTA BARBARA, CALIFORNIA

MEANS FOR PRODUCING DENSE CONCRETE ARTICLES

Application filed October 8, 1927. Serial No. 224,826.

This invention relates to a method of and means for producing dense concrete products, and is more particularly related to a method of producing concrete articles of substantially uniform density, including the filling of a mold with concrete and imparting to said mold before the concrete therein has set a non-directional oscillation.

In the production of concrete products, many efforts have been made in order to provide a means and method of increasing the density of the products by causing the constituents of the concrete to settle uniformly. The most successful method that, it is believed, has heretofore been proposed is the tamping of a so-called dry mix in a mold in order to force the constituent parts of the concrete together. Resort has also been made to bumping or jarring the methods in order to cause settling of the concrete. The difficulty encountered with this last method is that it separates the heavier constituents from the lighter, causing the heavier constituents to settle to the bottom of the concrete in the mold, leaving the light or finer particles on the top of the product, thereby producing an article of non-uniform density and likewise of non-uniform strength.

It is, therefore, an object of this invention to provide a method of producing concrete articles of substantially a uniform density and strength.

Another object of this invention is to provide a method of producing concrete articles of substantially uniform density and strength which includes the filling of a mold with concrete and imparting to the concrete in said mold before the same has set a non-directional oscillation.

Another object of this invention is to provide a means for producing concrete articles of substantially uniform density and strength including a frame, means for freely supporting the frame, and means operable in connection with said supporting means for imparting to said frame a non-directional oscillation.

Other objects and advantages of this invention, it is believed, will be apparent from the following detailed description of a pre-

ferred embodiment thereof. The means for carrying out the method embodying this invention are in their preferred form illustrated in the accompanying drawings.

In the drawings:

Figure 1 is a top plan view of an oscillator embodying this invention.

Figure 2 is a sectional side elevation thereof taken substantially on the line 2—2 of Figure 1.

Figure 3 is a sectional end elevation taken substantially on the line 3—3 of Figure 2.

Figure 4 is a sectional plan view taken substantially on the line 4—4 of Figure 3.

I have discovered that substantially uniform density may be obtained in concrete products if during the setting of the same or after the concrete has been poured into the molds, the concrete and molds are subjected for a short period of time to a rapid oscillatory motion which is non-directional. In using the term "non-directional", I am employing the same to indicate that the oscillations transmitted through the means embodying this invention, does not produce in the concrete in said molds a directional tendency of the heavier constituents of the concrete to travel in any one direction in said molds. I have found that such a non-directional oscillation may be obtained by oscillating a frame upon which the concrete article is supported in its mold, the frame being oscillated in one direction and supported loosely to permit the same to move freely in all directions and the frame which is being oscillated being also slightly out of balance on its respective supports, so that the oscillations imparted to the frame due to the unequal balance of the frame upon its free supports permits the frame to move in practically all directions uniformly.

In accordance with the method embodying this invention concrete, preferably of a wet mixture, is placed in a mold 1 which is supported on a frame 2. The frame 2 is then given an oscillatory motion through supporting means acting in conjunction with the power driven means for imparting motion to said frame 2 in such a manner that the supporting means and oscillating means cooper-

ate together to oscillate the frame 2 to produce in the concrete mold 1 a non-directional oscillation, causing the concrete to settle in the mold 1 to a substantially uniform density and strength in a very short period of time.

5 The use of the mold embodying this invention permits the concrete products to be formed of what is known as a wet mixture while the carrying out of this method produces a product of relatively great density and strength in that it causes the component particles of the concrete to settle extremely closely together while also not permitting directional setting of the heavier and lighter 10 particles, thereby producing a dense product which is of uniform density and uniform strength throughout.

15

The means provided in accordance with this invention for imparting to the frame 2 a non-directional oscillatory motion preferably include blocks 3 which are secured to the frame 2 at its corners and are provided with feet 4, which are freely supported in balls 5 in a ball and socket joint 6. The frame 25 is supported in the same manner at each of its four corners so that the supporting means for only one of said corners will be described. The ball and socket joint is mounted in a casing 7 to which a cap 8 is secured. The shank of the leg 4 extends 30 through holes formed in said cap 8. The cap 8 is provided with a circumferentially extending flange 9 within which a plurality of flexible balls 10 are mounted around said 35 shank to flexibly support the said shank at a point spaced from the ball 5. In place of the balls 10, a flexible ring formed of rubber or like material might be employed equally advantageously. The casing 7 is secured to 40 a concrete pier 11 by means of bolts 12. The balls 5 and 10 may be formed of rubber or like resilient, flexible material.

Means are provided for imparting an oscillatory motion to the frame 2, which means 45 preferably comprise a motor 13 which is supported upon a concrete pier 14. The shaft 15 of the motor 13 is secured through a flexible hose coupling 16 with a shaft 17 journaled in hangers 18 secured to the frame 2. Mounted on the shaft 17 at spaced points are 50 over-balancing weights 19 and 20 which may be formed of weighted wheels mounted eccentrically on the shaft 17. The over-balancing weight 19 is mounted eccentrically on the 55 shaft 17 in one position and the over-balancing weight 20 is mounted on the shaft 17 in a position preferably 180° away from the over-balancing weight 19.

The operation of the oscillatory means embodying this invention is: The motor 13 is 60 set in operation and acts to rotate the shaft 17 through the flexible coupling 16. The over-balancing weights 19 and 20 impart to the frame 2 a vibratory or oscillating motion which is directional in character ver-

tically. The free supporting of the frame 2 by the feet 4 on the balls 5 and the fact that the frame 2 will never be accurately balanced with a mold 1 thereon, tends to cause said frame to oscillate substantially in every 70 direction which oscillatory motion is permitted by the flexible coupling 16. The feet 4 are permitted to oscillate on the balls 5 by the flexible members 10 which yieldably hold the shanks of said feet, the feet 4 tending to roll on the balls 5 in a manner to cause the shanks thereof to wobble freely between the members 10. The supporting of the frame 2 in the manner heretofore described on the ball joints 6 functions together with the oscillatory means provided for oscillating the frame 2 to impart to the frame 2, and hence to the mold 1 and concrete therein, a non-directional oscillatory motion which causes the concrete in the mold 1 to settle to form 80 a dense product without imparting to the concrete a directional oscillatory motion which would tend to cause the heavier particles of the concrete to settle out in the direction of said directional oscillation.

90 The oscillation of the concrete in a non-directional manner, as heretofore specifically pointed out, causes the aggregates of the concrete or other similar material to displace the water and air to fill the voids which would otherwise be present in the concrete after setting due to the drying out or absorption of the water and the holes left in the product by the entrained air. The causing of the particles of the concrete to oscillate in a non-directional manner insures that all of the water and air which is not needed for the setting of the concrete will be displaced uniformly, causing the particles to interlace to form a very dense product. Merely bumping the concrete vertically will cause displacement of the water and air to some extent but will not cause the intimate interlacing of the particles of the concrete and the complete elimination of the excess water and the entrained air which is caused by oscillating the concrete in a non-directional manner, as there will be no tendency to move the particles horizontally to cause interlacing thereof as will result from the oscillation of the particles in 100 the manner heretofore described.

110 Having fully described my invention, it is to be understood that I do not wish to be limited to the details of construction of the apparatus herein described, nor to the application of the method embodying this invention to the settling of or forming of concrete products, but this invention is also applicable to the forming of other dense products such, for example, as molded products of diatomaceous earth, and the like, and my invention is of the full scope of the appended claims.

120 I claim:

130 1. In a device of the class described, the combination of a frame, a ball and socket

supporting means for said frame, and means for imparting an oscillatory motion to said frame supported on said balls and sockets.

6 2. In a device of the class described, the combination of a frame, means for supporting the frame to permit freedom of movement of the frame in any direction, said supporting means including housings, legs secured to the frame, ball and socket joints freely connecting the legs and housings within the housings, and means operably connected with the frame for imparting an oscillatory non-directional movement to the frame as supported.

10 3. In a device of the class described, the combination of a rectangular frame, means for supporting the frame at its corners to permit freedom of movement of the frame, said means including legs secured to the frame, 20 foundation supports at the corners of the frame, flexible ball and socket connections between the foundations and legs, means operably connected with the frame through a flexible coupling for imparting an oscillatory 25 non-directional motion to the frame.

30 4. In a device of the class described, the combination of a rectangular supporting frame, means for supporting the frame to permit freedom of motion of the frame, including a plurality of legs, a socket at the 35 end of each leg, complementary sockets secured in position in relation to each leg, a ball interposed between each pair of sockets, means for yieldably resisting the oscillatory motion of each leg, shaft journals and bearings secured to the frame, eccentric weights secured to the shaft in opposed relation, a motor for driving the shaft and a flexible coupling connecting the motor and the shaft.

40 Signed at Los Angeles, Calif., this 28th day of Sept., 1927.

JOHN COTTER PELTON.
